DAVID OLIVER, OF BERLIN, AND MAX POKORNY, OF HAMBURG-LOKSTEDT, GERMANY

DOOR

Application filed November 5, 1930, Serial No. 493,596, and in Germany November 9, 1929.

The invention relates to doors, which are intended for use in places where sloping floors are unavoidable, and particularly in theatres, concert halls, lecture halls and the like, and also for ramps leading for example, to motor-car garages with several stories, as well as for any other purposes where the flooring in front of the door is on a slope. Hitherto, there have been no known doors providing a satisfactory closure in the case of sloping surfaces of this kind. It is impossible merely to cut the door obliquely, to correspond with the slope of the floor, because, in such case it cannot be opened; but jams tightly at once. Consequently the general practice has been to provide a remedy by levelling that portion of the floor which is in front of the door, and sloping it only between doors. This, of course, is only a makeshift, since uniformity in the gradient of floors is desirable.

According to the present invention, the flooring in theatres or the like can be kept of uniform gradient, and in spite of this, to provide double doors which fit satisfactorily against the floor in all positions. This problem is solved by providing on the bottom edge of the door, a closure member which is adapted to tilt at the end next the hinge of the door, and to rise or drop when the door opens or closes. If the floor has a downward slope, away from the hinge of the door, the free end of the closure member will occupy its lowest position when the door is shut, and is gradually raised as the door opens. When the door is open at right angles, the lower edge of the closure member is horizontal, and as the door opens wider, the free end of said member is lifted still more, so that it lies on a higher level than the pivotal point. If the floor slopes upwards from the hinge of the door, the free end of the closure member is on a higher level than the pivotal point, when the door is shut. As the door opens to an angle of 90°, the closure member is lowered into the horizontal position. On the door being opened wider, the closure member descends still further, so that the free end is on a lower level than the pivotal point. In the simplest embodiment of the door, the closure

member is fitted to only one face of the door. The raising is effected by the thrust of the flooring in the act of opening and shutting the door. In order to improve the construction and aspect of the door, the closure member can be mounted so as to fit over both faces of the door, thus being of channel cross section, or it may also be recessed in the door.

In order to reduce friction, the bottom of the closure member may be fitted with rollers, balls, or the like, or other anti-friction devices. Finally, a cord and pulley device can be provided, so as to act on the free end of the member. The cord is led, for example, to a point in the hinge of the door, that is higher than the outer point of application, and then secured to the frame, so that it sustains a pull when the door is opening, and thus lifts the closure member. This arrangement is suitable for doors where the flooring slopes downwards from the hinge of the door.

If the door is intended to be opened in the opposite direction, a guide rod, to which the cord is attached, is provided on the free end of the door. The cord is passed round a pulley and led upwards to the hinge of the door. The rod, and therefore also the closure member descends the further the wider the door is opened. In this manner the closure member can be caused to slide in close proximity to the floor without touching it.

In order more clearly to understand the invention reference is made to the accompanying drawings which illustrate one embodiment of a double door in accordance with the invention and in which:—

Fig. 1 is an elevation of the door, in the closed position;

Fig. 2 is an elevation of the left-hand leaf open;

Fig. 3 is an elevation of the right-hand leaf open;

Fig. 4 is a plan of the left-hand leaf open;

Fig. 5 a plan of the right-hand leaf open; and

Fig. 6 is a section through the closure member along the line A—B of Fig. 1.

The door consists of the leaves *a* and *b*. The leaf *a* swings on the axis *X*, and leaf *b* on

the axis Y. The floor c slopes downwards from left to right, so that the leaf a swings on an upper axis, and leaf b on a lower axis. The leaf a is provided with a closure member d, and the leaf b with a closure member e, which are connected with the leaves a and b by means of joints. A cord f is attached to the free end of the leaf a and, after being led round a point g is fastened at h (Figs. 1 and

5 10 4). During the opening of the leaf a, the point g naturally moves away from the point h, and since the cord is fastened at h it is pulled through the door, for a certain distance x, the closure member d being lifted to 15 a corresponding extent (x, Fig. 1). The relative dimensions are so calculated that during the opening of the door, the closure member d is lifted throughout to such an extent that its lower edge slides close above the 20 floor all the time. When the leaf a is wide open, so that it bears against the chamfered wall i or the stop k (Fig. 4), the cord f will have raised the closure member d so far that the free end of the member d is on a higher 25 level than the end next the hinge of the door, and the lower edge of the closure member slopes upwards from the hinge.

The leaf b of the door is fitted with a rod l, adapted to move vertically in a sleeve t. The 30 rod l is acted upon by a spring m, the other end of which is attached inside the sleeve. Under the pull of the spring m, the rod l carries the closure member e by means of a ring n, adapted to move in a slot in the 35 sleeve, and of a cord o attached to the ring n and passed round a pulley r (mounted on the door) to a point p on the angle side of the door, where it is attached to the door frame at q. When the door is opened, the 40 cord o is drawn through the distance x, thereby pulling down the ring n for the same distance, and applying tension to the spring m. The rod l, and with it the closure member e is lowered accordingly. The relative 45 dimensions are in this case also calculated so that the closure member slides closely above the floor all the time the door is being opened. When the door is wide open, so that it makes contact with the wall i or 50 stop s (Fig. 5), the closure member e reaches its lowest position. The ring n has approached the pulley r to the fullest extent. The lower edge of the closure member e now 55 slopes downwards from the hinge of the door.

Rollers, balls or other antifriction devices are preferably provided on the under side of the closure member, the rollers coming into action in the event of the cord being broken through any cause.

Bottom closure members, for doors, which are adapted to be raised and lowered, or also swung, are known in themselves. These closure members however, are intended to cover 60 the gap, often met with between the door

and the floor, and thus keep out the draught. These closure members are used more particularly in cases where the floor has sunk, since, in such cases, the gap between the floor and the door is particularly large. However, the application of movable closure members to doors for ramp-like sloping floors has not hitherto been known.

What we claim is:—

1. In a door for ramp-like sloping floors in theatres or similar structures, a closure member fitted at the lower edge of the door and pivoted at the end next the hinge of the door, means for raising and lowering that closure member for predetermined amounts in accordance with the slope of the floor and with the angle at which the door is opened.

2. In a door for ramp-like sloping floors in theatres or similar structures, a closure member fitted at the lower edge of the door and pivoted at the end next the hinge of the door, a cord one end of which is attached to the free end of the closure member, the other end of which is hinged to the door and thence to the door frame for raising and lowering that closure member for predetermined amounts of the opening or closing of the door in accordance with the slope of the floor.

3. In a door for ramp-like sloping floors in theatres or similar structures, a closure member of channel cross section, surrounding both faces of the door, fitted at the lower edge of the door and pivoted at the end next the hinge of the door, means for raising and lowering that closure member for a predetermined amount in accordance with the slope of the floor and with the angle at which the door is opened.

4. In a door for ramp-like sloping floors in theatres or similar structures, a closure member fitted at the lower edge of the door and pivoted at the end next the hinge of the door, a rod guided in a sleeve and suspended from a spring for carrying that closure member, a cord one end of which is engaging with the upper end of the rod, the other end of which is hinged to the door and thence to the door frame for raising and lowering that closure member for predetermined amounts of the opening or closing of the door in accordance with the slope of the floor.

5. A door for ramp-like sloping floors as set forth in claim 1, in which antifrictional devices are provided on the under side of the closure member.

6. A door for ramp-like sloping floors as set forth in claim 1, in which rollers are provided on the under side of the closure member.

In witness whereof we have hereunto set our hands.

DAVID OLIVER.
MAX POKORNY.
